UNITED STATES PATENT OFFICE.

HENRY B. VAIL, OF ARLINGTON, OHIO.

PIG-BROODER.

No. 809,543.

Specification of Letters Patent.

Patented Jan. 9, 1906.

Application filed June 20, 1905. Serial No. 266,188.

To all whom it may concern:

Be it known that I, HENRY B. VAIL, a citizen of the United States, residing at Arlington, in the county of Hancock and State of Ohio, have invented a new and useful Pig-Brooder, of which the following is a specification.

My invention relates to animal-pens, and especially to pens for inclosing and caring for swine.

It is well known that great loss is occasioned to swine-breeders from the fact that at and shortly after parturition the mother often lies upon and kills the young.

An object of my invention is to provide a stall in which the mother is to be confined during labor and which has the lower edge of its side walls suspended above the floor of the pen to have a space sufficiently large for the young pigs to pass through out of harm's way, but prevent the passage of the mother.

It is well known that after birth the mother generally eats any still-born pigs and often continues by eating some of the live ones.

A further object of my invention is to provide a stall in which the mother may stand or lie, but of such a width as to prevent her from turning about.

A further object of my invention is to provide a stall which may be suspended within the pen and when its object is accomplished may be taken out and folded and stored in a flat state or hung up for further use.

A further object of my invention is to provide a device of the class in which the width of the stall may be varied to accommodate swine of different sizes.

With these and other objects in view the invention consists in the improved construction and novel arrangement and combination of parts hereinafter fully described, and particularly pointed out in the claims.

In the drawings, Figure 1 is a perspective view of my improved animal-pen with portions of the framework broken away to exhibit the operative parts. Fig. 2 is a top plan view of the stall sides and suspending-beams folded flat for storage. Fig. 3 is a longitudinal sectional view through the feed-box. Fig. 4 is a transverse sectional view of the improved animal-pen.

Like characters of reference designate corresponding parts throughout the several views.

In its preferred embodiment my improved animal-pen consists of a pair of vertical stall-walls 1, parallel to each other and secured at each end to the vertical beams 2. The stall-walls 1 are pivotally secured, by means of the vertical beams 2, to the beams 3, which extend entirely across the animal-pen and rest upon the side rails 4 or other convenient body. For pivoting the beams 2 to the beams 3 holes 5 and 6 are provided, through any of which may be inserted bolts 7 to adjust the stall to different widths and heights. The stall-walls are secured against displacement by the bars 8, slidably mounted in guides 9, and a slot through the beams 2 and engaging one of the slots 10, formed conveniently in the framework of the pen. The walls are further secured by notched braces 11, engaging cleats 12 upon the stall-walls and cleat 13 upon the side of the pen. The stall is secured from longitudinal displacement by the braces 14, engaged at one end within slots 15 in the pen-frame and notched slots 16. The stall-walls are provided at one end with the parallel cleats 17, forming a slot within which is disposed the end gate 18.

The stall-walls may be suspended within any pen; but I prefer to construct a pen especially for the purpose having the floor 19 and side walls 20 and the uprights 21 for supporting the side rails 4. At the front the stall has an open end registering with the feed-box 22, having a hinged cover 23, forming an opening to the outside for the introduction of feed, and beneath the pen are provided the skids or runners 23^a. Along one side the side wall 20 is provided with an opening 24, which may extend the entire length of the pen or so much thereof as may be found desirable. Upon the outside of the side wall and covering the opening 24 is a feed-box 25, having a hinged cover 26.

It will be noted that the stall-walls are suspended with their lower edges above the floor of the pen, and its operation is as follows: With the parts assembled as shown in Fig. 1, the animal is confined therein by disposing the open end against a building, fence, or the like and in the stall between the sides 1 shortly before parturition. When the young are delivered, they may pass out beneath the walls 1, and thus escape being laid upon by the mother. The width of the stall is also

such as to prevent the animal from turning around, and the still-born young may thus be removed before the mother has an opportunity of eating them, thus reducing to a minimum the liability of the mother eating her live offspring. For animals of different sizes the width of the stall may be varied, as indicated, by the use of the several slots and notches shown. When the stall has served its purpose, it may be removed and folded, as indicated in Fig. 2, and stored or hung in any convenient place. Instead of removing the entire stall one wall only may be removed, allowing the one nearest the trough to remain, thus making it possible for the pigs to pass thereunder and eat from the trough, which is thus rendered inaccessible to the mother or other adult hogs. If it is desired to remove the entire pen, the structure may be hauled or dragged on runners 23^a.

Having thus described the invention, what is claimed is—

1. In a device of the class described, the combination of, an animal-pen with a stall disposed therein and with its walls supported above the floor of the pen.

2. In a device of the class described, the combination of, an animal-pen with a stall suspended within the pen and with its walls above the floor of the pen.

3. In a device of the class described, the combination of, an animal-pen, a stall suspended within and with its walls above the floor of the pen, and means for bracing the stall from displacement.

4. In a device of the class described, the combination of, an animal-pen, a stall disposed within and with its walls above the floor of the pen, and means for varying the width of the stall.

5. In a device of the class described, the combination of, an animal-pen, a stall suspended within and with its walls above the floor of the pen, and means for varying the width of the stall.

6. In a device of the class described, the combination of, an animal-pen, a stall suspended within and with its walls above the floor of the pen, means for bracing the stall against displacement, and means for varying the width of the stall.

7. In a device of the class described, an animal-pen, a pair of beams removably extending across the pen, and a pair of stall-walls suspended from the beams and with their lower edges above the floor of the pen.

8. In a device of the class described, an animal-pen, a pair of beams removably extending across the pen, a pair of stall-walls suspended from the beams and with their lower edges above the floor of the pen, an end gate disposed to close the open end of the

stall, and means for bracing the stall against displacement.

9. In a device of the class described, an animal-pen, a pair of beams removably extending across the pen, a pair of stall-walls pivotally suspended from the beams and with their lower edges above the floor of the pen.

10. In a device of the class described, the combination of, an animal-pen, a pair of beams removably extending across the pen, a pair of stall-walls pivotally suspended from the beams and with their lower edges above the floor of the pen, an end gate disposed to close the open end of the stall, and means for bracing the stall against displacement.

11. In a device of the class described, an animal-pen, a foldable stall, and means for suspending the stall within the pen with a space between the lower edge of the stall-walls and the pen-floor.

12. In a device of the class described, the combination of, an animal-pen, a covered feed-box opening into said pen, a foldable stall, and means for suspending the stall within the pen with an open end registering with the feed-box and with an open space between the lower edge of the stall-walls and the pen-floor.

13. In a device of the class described, the combination of, an animal-pen, a foldable stall, means for suspending the stall within the pen with an open space between the lower edge of the stall-walls and the pen-floor, and means for bracing the stall against displacement.

14. In a device of the class described, the combination of, an animal-pen, a covered feed-box opening into said pen, a foldable stall, means for suspending the stall within the pen with an open end registering with the feed-box and with an open space between the lower edge of the stall-walls and the pen-floor, and means for bracing the stall against displacement.

15. In a device of the class described, the combination of, an animal-pen, a folding and adjustable stall, means for suspending the stall within the pen with a space between the lower edge of the stall-walls and the pen-floor, and means for varying the width of the stall.

16. In a device of the class described, the combination of, an animal-pen, a covered feed-box opening into said pen, a foldable and adjustable stall, means for suspending the stall within the pen with an open end registering with the feed-box and with an open space between the lower edge of the stall-walls and the pen-floor, and means for varying the width of the stall.

17. A device of the class described comprising, an animal-pen, a foldable and adjustable stall, means for suspending the stall with

in the pen with an open space between the lower edge of the stall-walls and the pen-floor, means for securing the stall against displacement, and means for varying the width of the stall.

18. A device of the class described comprising, an animal-pen, a covered feed-box opening into said pen, a foldable and adjustable stall, means for suspending the stall with
- 10 in the pen with an open end registering with the feed-box and with an open space between

the lower edge of the stall-walls and the pen-floor, means for securing the stall against displacement, and means for varying the width of the stall.

15 In testimony that I claim the foregoing as my own I have hereto affixed my signature in the presence of two witnesses.
